UNITED STATES PATENT OFFICE.

NICKOLAUS BINGER, OF PITTSBURGH, PENNSYLVANIA.

PLANE.

Application filed October 28, 1925. Serial No. 65,355.

My invention relates to planes and important objects thereof are to provide a device of the character stated, in a manner as hereinafter referred to which embodies 5 novel means for securing, adjusting and releasing the plane blade; which utilizes a comparatively short blade thereby providing for its economical replacement; which is simple in its construction and arrangement, strong, durable and efficient in its 10 use, compact, and comparatively inexpensive to manufacture.

With the foregoing and other objects in view which will appear as the description 15 proceeds, the invention resides in the combination and arrangement of parts and in the details of construction hereinafter described and claimed, it being understood that changes in the precise embodiment of 20 the invention hereinafter described and claimed can be made within the scope of what is claimed without departing from the spirit of the invention.

In the drawing wherein like numerals of 25 reference designate corresponding parts throughout the several views:—

Figure 1 is a longitudinal sectional view of a plane constructed in accordance with the invention.

Figure 2 is a similar view of the blade clamp.

Figure 3 is a bottom plan view of the blade-adjusting lever.

Figure 4 is a plan view of the inner side 35 of the clamp latch.

Figure 5 is a fragmentary sectional view of a modified form of the device.

Referring in detail to the drawing 1 denotes the metal body portion of the plane 40 consisting of the flat base 2 and the vertically disposed side walls 3 formed integrally with respective marginal side edges of the base 2.

The usual manipulation handles 4 and 5 are fixedly mounted on the base 2. The former is disposed at the rear end of the base 2 and the latter at the forward end thereof.

The base 2 is formed with a transversely 50 extending slot 6 for the projection of the cutting edge of the blade 7 and to provide clearance, forwardly of the latter, for the passage of the shavings during the planing operation. A transversely extending rib is 55 disposed rearwardly of the slot 6 and in conjunction with the rear wall of the latter,

provides an inclined seat 8 for the rear side of the blade 7.

A clamp 9, provided with a pair of rearwardly extending, parallel disposed ears 10 adjacent to its lower end, is pivotally 60 mounted on the transversely extending rod 11. The latter has its ends fixed in respective side walls 3, adjacent to the lower end thereof, and extends through the apertures 12 provided therefor in the ears 10. The clamp 9 is disposed in an inclined position in the body portion 1 and the lower end 13 thereof is curved rearwardly to provide an inclined contact face 14 to normally 70 squarely engage the lower end of the blade 7 in the slot 6. The curvature of the clamp end 13 further prevents retardation to the passage of shavings through the slot 6. The clamp 9 is further constructed to provide 75 a recess 15 directly forward of the ears 14 to provide clearance for the operation of the blade adjusting lever 16, to be described.

The lower side of each of the ears 10 is formed with a notch 17. The notch 17 of 80 one ear 10 is disposed parallel relatively to the notch in the other of the ears, and the same engage the marginal top edge of the blade 7 and provide the normal adjustment of a new blade in the plane.

The adjusting lever 16 is disposed longitudinally in the body portion 1 and is formed with a pair of depending apertured ears 18, which are pivotally mounted on the rod 11, inwardly of the clamp ears 14. The forward end 19 of the lever 16 is disposed at an angle to engage the top edge of the blade 7 and is formed with a short depending flange 20, which overlaps the top edge of the blade 7 and prevents liability of disengagement of the forward lever end 19 from its position on the top edge of the blade 7. The rear end of the lever is formed with a threaded aperture 21 in which is mounted an adjusting screw 22. The lower end of the latter engages the base 1, and the manipulation of the screw 22 provides for the adjustments of the blade 7 through the slot 6 by the operation of the associated lever 16.

The clamp 9 is secured in the clamping position by the clamp latch 23. The latter is provided with a pair of apertured cam ears 24, which are pivotally mounted on the transversely disposed rod 25 fixed in the side wall 3 adjacent to the upper end thereof. The latch 23 is forced forwardly

and disposed in the vertical position, as shown, in Figure 1, of the drawing, when the ears 24 engage the rear face of the clamp 9 to secure the blade 7 in the adjusted position, so that the latch 23 will not interfere with the operator's hand while grasping the handle 4 in operating the plane.

10 The modified form of the device, shown in Figure 5, of the drawing, is identical in operation and somewhat similar in construction to the preferred form above described.

15 The body portion 26 differs from the preferred form in that the side walls 27 thereof are formed with a transversely extending bar 28 having an inclined forward portion 29. The clamp 30 and cam latch 31 are pivoted on a common rod 32 and the cam latch 31 engages and operates on the outer face of the inclined bar portion 29. The rear end of the blade adjusting lever 33 is formed with an open slot 34 in which the lower end of the T-bolt 35 is engaged. The 20 upper end of the latter extends through an aperture 36 in the bar 28 and is engaged by the adjusting nut 37. The manipulation of the nut 37 will adjust the blade to the cutting position in the body portion 26.

25 A spring 38 is carried on the under side of the bar portion 29 and engages the adjusting lever 33 for normally maintaining a tensional pull on the T-bolt 35 thereby preventing the disengagement of the latter from the lever 33 during the adjusting operation.

30 It will here be noted that a comparatively short blade is used in connection with my improved plane thereby providing for 40 its economic replacement. The shortness of the blade together with the manner of mounting the latter in the body portion of the plane will prevent chattering of the blade and provide a most substantial efficient tool.

45 What I claim is:

1. In combination, a plane comprising a body portion consisting of a base and a pair of integrally formed side walls, said base provided with a transversely disposed slot, a clamp pivotally supported by said side walls, a blade having its cutting edge disposed in said slot, an adjusting lever pivotally supported by said side walls and

engaging the top edge of said blade for adjusting the latter in said body portion, and 55 means for actuating said clamp to secure said blade in the adjusted position.

2. In combination, a plane comprising a body portion consisting of a base provided with a pair of integrally formed side walls, 60 said base formed with a transversely disposed slot, a blade having its cutting edge disposed in said slot, a transversely disposed supporting rod mounted in said side walls, a clamp provided with a pair of apertured ears, said clamp ears pivotally connected to said supporting rod, each of said clamp ears formed with a notch engaging the upper end of said blade, the lower end of said clamp being curved rearwardly and 70 engaging the said blade, a blade adjusting lever provided with a pair of ears pivotally connected to said supporting rod and engaging the top edge of said blade, and a cam latch pivotally supported by said walls 75 and shiftable to actuate said clamp for locking said blade in the adjusted position.

3. In combination, a plane comprising a body portion consisting of a base provided with a pair of integrally formed side walls, 80 said base formed with a transversely disposed slot, a blade having its cutting edge disposed in said slot, a transversely disposed supporting rod mounted in said side walls, a clamp provided with a pair of apertured ears, said clamp ears pivotally connected to said supporting rod, each of 85 said clamp ears formed with a notch engaging the upper end of said blade, the lower end of said clamp being curved rearwardly and engaging the said blade, a blade adjusting lever provided with a pair of ears pivotally connected to said supporting rod and 90 engaging the top edge of said blade, and a cam latch pivotally supported by said walls and shiftable to actuate said clamp for locking said blade in the adjusted position, said clamp formed with a recess on its 95 rear side to provide clearance for the operation of said blade adjusting lever, substantially as described and for the purpose set forth.

In testimony whereof I affix my signature.

NICKOLAUS BINGER.
